UNITED STATES PATENT OFFICE.

LEVI E. WESCOTT, OF CUMBERLAND MILLS, MAINE.

HORSESHOE-ANVIL.

SPECIFICATION forming part of Letters Patent No. 411,405, dated September 17, 1889.

Application filed April 13, 1889. Serial No. 307,128. (No model.)

To all whom it may concern:

Be it known that I, LEVI E. WESCOTT, of Cumberland Mills, in the county of Cumberland and State of Maine, have invented certain new and useful Improvements in Horseshoe-Anvils; and I do hereby declare the following to be a full, clear, and exact description of the invention, such as will enable others skilled in the art to which it appertains to make and use the same.

My invention relates to an improvement in horseshoe-anvils.

It has been found by experience that the calks of a horseshoe, in order to produce the best results, should have a perfectly straight taper when sharpened, and not have their sides—one or both—curved, and it is also found desirable that the opposite sides of the taper should be oblique and gradually approach each other, rather than one side straight and the other taper toward it. To construct calks of the above form has hitherto required considerable time and numerous blows of the blacksmith's hammer.

The object of my present invention is to provide a device by means of which the shoe can be held firmly in position by the foot with the calk resting on a swage of such form that a single or a very few strokes from the hammer will shape the calk into the desired form.

With these ends in view my invention consists in certain features of construction and combinations of parts, as will be hereinafter described, and pointed out in the claims.

In the accompanying drawings, Figure 1 represents the anvil and its attachments in side elevation, showing a shoe held thereby with its calk resting on the swage in position to be shaped. Fig. 2 is a similar view showing the shoe-holding jaw in released adjustment and the swage removed from its seat. Fig. 3 is a top plan view, and Fig. 4 represents a modified form of swage.

A represents a base or pedestal, from which uprises a standard B. The standard B may either be formed integral with the base or it may be formed in one or more parts and firmly secured to the base. In the present instance it terminates at the top in a heavy metal head b, adapted to withstand the blow of the hammer. The standard B has pivotally secured

thereto below the head b a curved lever C, one end of which c is so shaped that when its operating end c' is depressed its gripping-face c² will abut against the outer face of a swage D, projecting above the top of the head b, or against both the head b and the upwardly - extended portion of said swage. The end of the part c of the lever C is re-enforced back of its gripping-face c², as shown at c³, and the said lever is held normally in released adjustment by means of a spring E, connecting its part c with the standard B.

The lever C is operated to grip the shoe between its face and the swage by means of a lever F, pivoted at one end, as at f, in the standard, and projecting forwardly into a convenient position for receiving the foot of the operator. The lever F is connected with an intermediate lever G, pivoted, as at g, in the standard B by means of a link or connecting-rod H, which loosely connects the free end of the lever G with the lever F at a point intermediate of its fulcrum and its free end. In the same manner the end of the part c' of the lever C is connected with the intermediate lever G by a link or connecting-rod h. By this construction a powerful grip is obtained without extending the arms of a lever to an unwieldy and inconvenient length.

In the head b and on the rear side thereof a socket I is formed to receive a swage D and allow the same to project a short distance above the top of the head, as shown. The top d of the swage D is beveled, as shown, to give the proper taper to the calk, and for the purpose of giving different tapers, as the demands of the shoe may require, interchangeable swages D are furnished and provided with different angles of bevel. I find it convenient to form the socket I dovetail in cross-section, as this serves to retain the swage in position.

The shoe K, with its calk k resting on the beveled end of the swage, is securely held in position by downward pressure on the foot-lever F, and by striking the exposed face of the calk a sharp square blow it will be forced into the desired form. The re-enforced end of the lever C will serve to counteract the tendency, if any there be, for the calk to slide on the beveled end of the swage, and

all the smith will be obliged to observe is that he make the exposed surface of the calk the proper bevel, as the lower surface will conform to the bevel of the end of the swage. A 5 calk can thus be shaped at a single blow in many instances, and in every instance much quicker and more perfect than by the ordinary method.

It is evident that slight changes might be 10 resorted to in the form and arrangement of the several parts without departing from the spirit and scope of my invention, and hence I do not wish to limit myself strictly to the construction herein set forth.

15 I have shown in Fig. 4 one of several different forms which the swages employed may assume, the same being simply constructed to give slightly-varied degrees of taper or to afford a better grip for the shoe, as the re- 20 quirement may demand.

Having thus fully described my invention, what I claim as new, and desire to secure by Letters Patent, is—

1. The combination, with a suitable support 25 and a removable swage seated in the top of the support, of a vibrating lever pivoted to the support, the upper end of the lever being in position to abut against the removable swage, and a foot-lever pivoted to the support 30 and connected with the said vibrating lever, substantially as set forth.

2. In combination, a suitable support, a lever pivoted in said support and provided with a horizontal arm and with an upwardly-extending arm, a swage removably seated in 35 the top of the support, the upper end of the swage being horizontally opposite the upper end of the upwardly-turned arm of the lever, a foot-lever pivoted to the support, and a connection between the foot-lever and the horizontal end of the first-named lever, substantially as set forth.

3. In combination, a suitable support, a swage removably seated in its head, a lever pivoted to the support and provided with an 45 upwardly-extending gripping-arm, a foot-lever pivoted to the support, an intermediate lever pivoted to the support, connections between the intermediate lever and the gripping and foot levers, and a spring for holding 50 the gripping-lever in released adjustment, substantially as set forth.

In testimony whereof I have signed this specification in the presence of two subscribing witnesses.

LEVI E. WESCOTT.
